WATER METER COVER

Emil M. Krueger, Milwaukee, Wis., assignor to
Badger Meter Manufacturing Company, Mil-
waukee, Wis., a corporation of Wisconsin

Application December 14, 1932, Serial No. 647,115

12 Claims. (Cl. 220—82)

This invention relates to improvements in water meter covers.

It is the primary object of the invention to provide a dual cover organization for a conventional water meter casing whereby the usual glazed cover is protected by a solid metal cover so designed that when the solid metal cover is closed over the glazed cover both covers will be releasably locked in place to maintain a water-tight gasket under adequate compression.

In the drawing:

Figure 1 is a side elevation of the cover unit plate to a water meter casing.

Figure 2 is a view taken in transverse section in a vertical plane.

Figure 3 is a plane view of the apparatus showing the protecting cover in a raised position and partially broken away.

Like parts are identified by the same reference characters throughout the several views.

To the meter casing 4 is applied a dial housing 5 having hinge ears 6 and 7 at its front and rear. The usual glazed cover 8 has knuckles 9 spaced to receive hinge ear 7 and connected thereto by means of a pintle 10. It is provided with a cover glass 12 in the usual manner to permit inspection of the dials encased within the housing 5. A gasket 14 carried by the under surface of the glazed cover 8 is engageable with the top margin of housing 5 to provide a liquid tight seal between the housing and the glazed cover.

The ears 6 carry a pintle 15 upon which the knuckles 16 of the auxiliary cover 17 are pivoted. The auxiliary cover fits closely over the glazed cover as is clearly shown in Fig. 2.

The glazed cover differs from conventional practice in that it is provided at 18 with an arm which overlies the pintle 15. The space between the ears 16 of the auxiliary cover 17 is closed above pintle 15 by a web 19 upon the under surface of which is preferably formed a cam 20. The form of the cam is such that as the auxiliary cover 17 approaches the lower position, in which it is illustrated in Figs. 1 and 2, the cam 20 will engage the free end of arm 18 to compress the glazed cover downwardly to a firm seat on housing 5. The pressure of the cam upon arm 18 gradually increases until the nose of the cam passes the end of the arm, after which the pressure is very slightly relieved. The parts are sufficiently resilient so that this slight relief of pressure does not involve any separation of the cam and the arm, the compression of gasket 14 on the housing being maintained in the closed position of the auxiliary cover. The relief of pressure is just

sufficient so that there is a tendency for the interaction of the cam and arm 18 to maintain the auxiliary cover tightly upon its seat on the glazed cover. Thus the interaction of the cam and arm serves, in the Fig. 2 position of the parts, to hold both covers in their proper relation to each other and to the housing.

The mere act of opening the auxiliary cover 17 not only exposes the meter dials to view through glass 12, but also makes it possible for the operator to raise the glazed cover and thus to gain access to the dials by breaking the customary seal at 21. In other words, no securing device is required for the glazed cover other than the auxiliary protective cover as above described.

I claim:

1. In a cover organization, the combination with a housing member, of a pair of covers hingedly connected therewith and adapted to overlie said housing in superposed relation, one of said covers being substantially rigid and having a resilient projecting arm, and means acting solely between said arm and the other cover member comprising a detent for holding both of said cover members in said relation, said arm being yieldably distorted by the engagement of the detent therewith, whereby to provide a yielding pressure tending to hold said covers in superposed relation.

2. In a cover organization, the combination with a housing member, of cover elements separately hinged thereto and movable to superposed positions upon said housing member, and detent cam parts comprising parts of said cover elements interacting in the hinged movement of one of said elements with respect to the other to subject said elements to pressure tending to maintain them in superposed position upon the housing, one of said parts being resilient and arranged to be distorted in the process of moving said elements to superposed positions whereby yieldably to provide such pressure.

3. In a cover organization, the combination with a housing member, of cover elements having projecting portions hinged to said housing member at opposite sides thereof, said elements being movable to superposed positions upon said member, one of said elements having an arm underlying the hinged portion of the other, and said hinged portion having a cam engageable with said arm to compress the first element upon the housing as the second element is moved to said superposed relation.

4. In a cover organization, the combination with a housing, of a glazed cover hinged to the housing and provided with a resilient arm re-

mote from its hinge, a protective cover hinged to the housing adjacent said arm and provided with a cam portion adapted to overlie said arm as the protective cover approaches its closed position overlying the glazed cover, said cam portion being constituted to engage and depress said arm and to compress the glazed cover upon the housing, distortion of said arm under such pressure serving to maintain the pressure between said glazed cover and said housing.

5. In a cover organization, the combination with a housing, of a glazed cover hinged thereto having a substantially rigid frame and provided opposite its hinge with a resilient arm, a hinged 10 pintle adapted in the closed position of said glazed cover to underlie said arm, a protective cover hinged on said pintle and provided with cam means interacting with said arm in a direction to depress and distort said arm and to 15 press said glazed cover yieldingly to said housing in the course of the closing movement of said protective cover.

6. In a cover organization, the combination with a housing, of a glazed cover hinged thereto 20 and provided opposite its hinge with a resilient arm, a hinge pintle adapted in the closed position of said glazed cover to underlie said arm, a protective cover hinged on said pintle and provided with cam means interacting with and 25 distorting said arm in a direction to yieldingly press said glazed cover to said housing in the course of the closing movement of said protective cover, said cam means being adapted to pass the free end of the arm as the protective cover 30 is closed, whereby to maintain the protective cover, as well as the glazed cover, under a pressure tending to maintain said covers in closed position, the resiliency of said arm operating to 35 maintain the pressure between said cam means and said arm after said cam means has passed the free end of said arm as aforesaid.

7. A hinge and latch combination including a pair of spaced knuckles, a pintle extending between said knuckles, a resiliently yieldable detent 40 arm in one position extending between said knuckles and overlying said pintle, and a cam between said knuckles and connected therewith for movement about said pintle and positioned to engage said arm in the course of movement of 45 said knuckles about the axis of said pintle and across a predetermined center line, the resilient distortion of said arm by said cam being adapted to provide a reaction pressure tending to maintain said knuckles and cam in a position of 50 engagement with said arm and across said center line.

8. In a cover organization, the combination with a housing, of a glazed cover hinged to said housing and having an arm extending therefrom opposite said hinge, a protective cover having a pair of knuckles extending therefrom in spaced relation, a pair of spaced ears extending from said housing between said spaced knuckles and positioned to receive said arm between them in the closed position of said glazed cover, a 55 pintle extending through said ears and knuckles and underlying said arm in said closed position, and a cam between said knuckles and positioned

to engage said arm and force said glazed cover into sealing contact with said housing upon closing of said protective cover.

9. In a cover organization the combination with a housing, of a glazed cover hinged to said housing and having an arm extending therefrom opposite said hinge, a protecting cover having a pair of spaced knuckles extending therefrom, and positioned to receive said arm between them in the closed position of said glazed cover, said arm being positively centered between said knuckles in such closed position of said glazed cover, and a cam between said knuckles positioned to engage said arm during closing movement of said protecting cover and to force said glazed cover 15 into accurate sealing relation with said housing.

10. In a cover organization the combination with a housing, of a glazed cover hinged to said housing and arranged to be seated in sealing relation on said housing, a protective cover arranged to close over said glazed cover, a pintle carried by said housing and on which said protective cover is hinged to said housing, said protective cover having a peripheral flange extending downwardly about said glazed cover, a 20 cam carried by said protective cover and disposed above said pintle, and an arm extending from said glazed cover beneath said flange, curving upwardly over said pintle, and arranged to be depressed toward said pintle by said cam upon 25 closing of said protective cover over said glazed cover.

11. In a meter closure the combination with a casing having an upwardly extending rim, of a substantially rigid frame hinged to said casing 30 and arranged to rest on said rim, said frame having a channel for the reception of a gasket and bounded by an outer downwardly extending flange encircling said rim and a portion of said casing, a transparent element carried by said frame and a gasket in said channel, a resilient arm extending from said flange, a protective cover hinged to said casing opposite the point at which said frame is hinged thereto, and means 35 on said cover engaging said resilient arm and forcing said frame and gasket into contact with said rim when said cover is closed over said frame.

12. In a meter closure the combination with a casing having an upwardly extending rim, of a substantially rigid frame hinged to said casing 40 and arranged to rest on said rim, said frame having a channel for the reception of a gasket and bounded by an outer downwardly extending flange encircling said rim and a portion of said casing, a transparent element carried by said frame and a gasket in said channel, a resilient arm extending from said flange, a protective cover hinged to said casing opposite the point at which said frame is hinged thereto, a downwardly extending rim on said protective cover 45 encircling said frame and extending between said frame and said resilient arm when said cover is closed, and means on said cover engaging said resilient arm and forcing said frame and gasket into sealing contact with said upwardly extending rim when said cover is closed over said frame.
